EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FILLING-REPLENISHING LOOM.

1,325,216.

Specification of Letters Patent.

Patented Dec. 16, 1919.

Application filed August 7, 1919. Serial No. 315,964.

To all whom it may concern:

Be it known that I, EDWARD S. STIMPSON, a citizen of the United States, and a resident of Hopedale, in the county of Worcester and 5 State of Massachusetts, have invented an Improvement in Filling-Replenishing Looms, of which the following description, in connection with the accompanying drawings, is a specification, like characters on the drawings representing like parts.

This invention relates to filling replenishing looms and more particularly to means for preventing breakage or injury to parts when, on call for replenishment of filling, a 15 filling carrier is improperly positioned for transfer.

In looms of the filling replenishing type wherein a fresh supply of filling is automatically transferred from a magazine or hopper to the shuttle when the supply of filling in the shuttle has become exhausted, it is now the common practice to provide means for actuating the transferrer only upon call for filling replenishment. In one well-known type of filling replenishing loom, the 20 hopper is of the rotary character and is adapted to hold a series of filling carriers, such as bobbins, which are brought successively into transferring position by rotary movement of the hopper following each call for filling replenishment. In this type of loom the principal duty of the weaver is to keep the hopper supplied with filling carriers. In placing the filling carriers in 25 the rotary hopper, the weaver disengages the hopper actuating and holding means from the hopper, and rotates the hopper by hand as he or she places the filling carriers with a fresh supply of filling thereon in the hopper. During this time the loom continues in 30 operation, there usually being still a number of filling carriers in the hopper ready for transfer.

Should a call for replenishment of filling 35 be made by the now well-known forms of mechanisms for this purpose, during the time the weaver is supplying the hopper with filling carriers, a filling carrier may not be in proper position for transfer, or, 40 when the weaver has finished his task of supplying the hopper with filling carriers, he or she may leave the hopper with a filling

carrier improperly positioned for transfer but yet in the path of the transferrer. Under these conditions should a call for 55 replenishment of filling occur, the transferrer will be operated, but the filling carrier being not in proper position for transfer, yet in the path of the transferrer, breakage or 60 injury to some of the parts is liable to occur.

An important feature of the present invention, therefore, consists in means for alternatively rotating the hopper to carry an 65 improperly positioned filling carrier from the path of the transferrer or prevent operation of the transferrer upon call for filling replenishment when the filling carrier is not properly positioned for transfer in the path of the transferrer. As a good practical form of the present invention with respect to the 70 feature referred to, the holding means for the hopper is utilized to position a detent in the path of the dog or finger which is connected to the transferrer and is moved to operative position with respect to a part on 75 the lay upon call for filling replenishment, the effect being that either the holding means causes rotary movement of the hopper to carry the improperly placed filling carrier out of the path of movement of the 80 transferrer, or, failing in this, it prevents movement of the dog or finger to operative position and, therefore, prevents operation of the transferrer.

Other features of the invention and novel 85 combinations of parts will hereinafter be described in connection with the accompanying drawings which illustrate a good, practical form of the invention, and then the novel features and combinations will be defined by the claims.

In the drawings:

Figure 1 is a perspective view of a portion of a filling replenishing loom at the replenishing side, showing more particularly 95 the hopper and associated parts;

Fig. 2 is a vertical transverse section through the hopper and lay showing the position assumed by the parts when a filling carrier is improperly presented for transfer 100 in the path of the transferrer;

Fig. 3 is a view similar to that of Fig. 2 showing the parts in the position assumed when the hopper is given its backward ro-

10 tary movement to carry an improperly positioned filling carrier out of the path of the transerrer.

15 The loom frame 1 may be of usual form and suitable character for supporting the operating parts. Secured to the loom frame is a bracket 2 from which rises the stationary head 3 of the rotary hopper which is mounted for rotary movement on a shaft 4 carried by the head.

20 Mounted in the suitable supporting portion 5 of the bracket 2 is the stud or arm 6 on which is mounted the transerrer 7 normally maintained in its upward or inoperative position by means, such as a spring 8, or other suitable means. Extending downwardly from the hub portion 9 of the transerrer is an arm 10 to which is pivotally connected at 11 the swinging dog or finger 12 to which is connected a pin 13 extending into the slotted portion 14 of an arm 15 carried at 16 by a part of the usual shuttle feeler, commonly used in this type of loom, the construction being such that upon call for replenishment of filling the slotted arm 5 is moved clockwise, viewing Figs. 2 and 3, to permit the dog or finger 12 to move upwardly from the position in Fig. 2 to that of Fig. 3 into the path of a bunter 17 carried by the lay 18. As the lay moves forward, with the parts in position as indicated in Fig. 3, which results upon call for filling replenishment, the bunter 17 strikes the notched end portion 19 of the dog or finger 21, and by further forward movement causes the transerrer to be operated to transfer a filling carrier 20 from the hopper to the shuttle beneath. The parts so far described are of usual construction in this type 40 of filling replenishing loom and being well understood by those skilled in the art, further detailed showing or description of this portion of the mechanism, is unnecessary.

25 The rotary hopper consists of the heads 21 and 22 secured upon a sleeve 23 rotatably mounted upon the shaft or support 4, and these heads, as usual, have means for holding the ends of the filling carriers or bobbins 20, as indicated in Fig. 1.

30 Secured to the rotary hopper is a toothed disk 24 by which, through the means presently to be described, a hopper is given its rotary movement clockwise, viewing Figs. 2 and 3, to place a filling carrier in transferring position. Rotary movement of the hopper after transfer of a filling carrier may be effected by variously contrived means, but in the present instance of the invention the transerrer 7 has pivotally mounted thereon at 25 an actuator 26 carrying a tooth 27, which, as the transerrer moves downwardly during its transfer movement, clicks over the teeth of the toothed disk 24, and on upward movement of the transerrer causes 65 rotary movement of the hopper to present

another filling carrier 20 to transferring position.

When a filling carrier is in transferring position, its leading side rests against an abutment 27, Figs. 2 and 3, and upon downward movement of the transerrer 7 the filling carrier which is properly positioned for transfer and bearing against the abutment, is passed through the throat 28 downwardly into the shuttle beneath. When a filling carrier is in proper transferring position, it is desirable that rotary movement of the hopper be prevented, and to this end, in the present instance, a holding finger or pawl 29 is pivotally mounted at 30 to the bracket 5 or a fixed part of the loom, and at its upper end carries a holding pawl 31, which, by engagement between the teeth of the disk, locks or holds the rotary hopper from rotary movement and with a filling carrier in proper transferring position bearing against the abutment 27. The parts thus far described may be of usual character well understood by those skilled in the art, and, as more fully explained in the patent to Edward S. Stimpson No. 664,790, dated December 25, 1900.

When the weaver desires to place filling carriers in the rotary hopper, he usually disengages the actuator 26 and the holding pawl 31 from engagement with the toothed disk, thereby freeing the hopper to manual rotation. During the time the weaver is filling the hopper with filling carriers, the loom continues to run, and if, during this period there should be a call for replenishment of filling effected by the usual filling detecting mechanism, it is desirable that actuation of the replenishing mechanism be prevented. This is particularly true with respect to the so-called "feeler looms" wherein a call for a change of filling is announced prior to the complete exhaustion of the filling in the shuttle, so that even though a call for filling replenishment may be made while the hopper is being filled, it is desirable that the old filling still in the shuttle shall continue to lay its length in the shed, without the production of imperfect cloth and until the weaver can manually turn the hopper to present a filling carrier to transferring position.

It happens at times also that when the weaver has completed his task and released the actuating member 26 and the holding member 31, a filling carrier will not be properly positioned for transfer; that is, the weaver may release the actuating and holding means when a filling carrier is in the position, as indicated in Fig. 2, wherein it will appear that while the filling carrier is not in proper transferring position, it is yet in the path of movement of the transerrer, consequently, should filling replenishment be attempted to be effected at this time, the transerrer would not be able to transfer the

improperly positioned filling carrier and breakage or injury of some of the parts is liable to ensue.

The present invention contemplates means for preventing such improper action and resulting injuries, either by preventing the transferrer from being operated, or by moving the rotary hopper to carry the improperly placed filling carrier out of the path 10 of movement of the transferrer.

The holding means or pawl carrier 29 has a downwardly extending portion 32 which is connected to a detent 33, the lower end portion 34 of which is adapted to be engaged 15 by the dog or finger 12, as the latter is moved upwardly to operative position. The detent 33, in the present instance of the invention, is pivotally mounted at 35 to a fixed part of the loom, such as the bracket 2, and 20 its upwardly extending bifurcated end 36 engages a pin 37 extending from the portion 32 of the holding pawl carrier 29. Should the detent 33 be moved counterclockwise, as viewed in Fig. 2, by the dog or finger 12, as 25 the latter moves upwardly into operative position, the upper end or holding pawl 31 of the carrier 29 will be moved inwardly. Should the weaver, upon finishing his task of filling the rotary hopper with filling carriers, release the parts so that they assume 30 the position indicated in Fig. 2, with the holding tooth 31 resting upon the inclined portion 38 of a tooth of the toothed disk, then such movement of the detent by the 35 dog or finger will move the holding pawl 31 into or toward the bottom of the space between the teeth of the toothed disk and, perforce, cause rotation of the toothed disk and connected rotary hopper backwardly, to 40 thereby remove the improperly positioned filling carrier 20 from the path of movement of the transferrer. This condition is illustrated in Fig. 2 and the resulting condition of movement of the detent 33 by the dog 45 or finger 12 is indicated in Fig. 3 and where it will be seen, as indicated by the arrow, the rotary hopper has been moved backwardly to carry the misplaced filling carrier 20 out of the path of movement of the transferrer. The conditions above described are 50 probably of most frequent occurrence, but it may sometimes happen that the holding pawl 31 may engage a tooth of the toothed disk 24 on the opposite slant of the tooth, in 55 which case the inward movement of the holding pawl will effect movement of the rotary hopper to position the improperly positioned filling carrier and bring it firmly against the abutment 27. In either case, 60 however, no injury results to the parts.

Should the weaver, in completing his task, release the parts so that the pointed end of the pawl 31 may rest upon the end portion of one of the teeth of the toothed disk 24, 65 the detent 33 may not be effective in rotat-

ing the hopper, in which event the detent 33 remains in fixed position and prevents movement of the dog or finger 12 to its upward or operative position, and thereby prevents operation of the transferrer.

The detent 33 may be variously contrived to perform its described function, but in the present instance of the invention, and in order to adapt it to various conditions of use, it is formed in two parts adjustably secured 70 together by a bolt 39, this construction being best illustrated in Fig. 1.

The dog or finger 12 may be variously contrived to cooperate with the end 34 of the detent 33, but in the present instance of 80 the invention the upper surface portion of the dog 12 is provided with a shoulder 40 which, as the dog or finger 12 is moved into operative position, as indicated in Fig. 3, engages the end 34 of the detent 33 and 85 causes movement of the detent counterclockwise, viewing Fig. 2, should the holding pawl be not properly engaged with a holding tooth on the toothed disk 24. If, however, movement of the holding pawl 31 into 90 full engagement with the recess between the teeth is prevented, as by the pawl 31 engaging the end of a tooth on the disk, then the end 34 of the detent 33, by engagement with the upper surface of the dog or finger 12, 95 will arrest or stop the upward movement of the dog or finger before it reaches operative position and, perforce, prevent operation of the transferrer.

From the construction described it will 100 appear that should a call for filling replenishment occur during the time the attendant is manually restraining the holding pawl from engagement with the teeth of the ratchet disk, the detent 33 will prevent movement of the dog or finger 12 to operative position and thereby suspend or prevent operation of the transferrer until such time as the weaver may place a filling carrier in proper transferring position by rotation of 110 the hopper. Also, should the weaver release the holding pawl so that it does not fill in between the teeth of the ratchet disk, then upon call for filling replenishment, the detent will be actuated by the dog or finger 115 12 and cause rotation of the hopper, either to move a filling carrier away from transferring position and out of the path of the transferrer, or, as may sometimes happen, into transferring position for the action of 120 the transferrer. In any event, improper and injurious operation of the parts is prevented.

Claims:

1. In a filling replenishing loom, the combination of a rotary hopper, a toothed disk 125 connected thereto, a holding pawl carrier adapted by full engagement with teeth of the disk to prevent rotation of the hopper, a transferrer, a dog or finger connected thereto and movable to operative position on 130

call for filling replenishment, a detent engaged and moved by the dog or finger as the latter moves toward operative position and connections between the holding pawl carrier and detent to move the holding pawl carrier and cause rotary movement of the hopper when the detent is moved by the dog or finger.

2. In a filling replenishing loom, the combination of a rotary hopper having a toothed disk, a holding pawl carrier for engaging the teeth of the disk and holding it from rotation when a filling carrier is properly positioned for transfer, a detent pivotally mounted independent of the holding pawl carrier, a connection between the detent and holding pawl carrier, a transferrer, a dog or finger connected to the transferrer, means for moving it toward operative position on call for replenishment of filling, said detent being positioned for engagement by the dog or finger as it moves to operative position to cause the detent to be moved and operate the holding pawl carrier to rotate the hopper when a filling carrier is improperly positioned in the path of the transferrer and the filling is to be changed.

3. In a filling replenishing loom, the combination of a rotary hopper for holding a supply of filling carriers, a transferrer, means for holding the hopper from rotary movement when a filling carrier is properly positioned for transfer, a dog or finger connected to the transferrer, means for moving it toward operative position upon call for replenishment of filling, and a detent member actuated by the dog or finger connected to the holding means for the hopper to alternatively prevent movement of the dog or finger to operative position or to rotate the hopper when a filling carrier is improperly positioned for transfer in the path of the transferrer on call for replenishment of filling.

4. In a filling replenishing loom, the combination of a rotary hopper for holding a supply of filling carriers, a transferrer, means for holding the hopper from rotary movement when a filling carrier is properly positioned for transfer, a dog or finger connected to the transferrer, means for moving it toward operative position upon call for replenishment of filling, and a detent member connected to the holding means for the hopper and having a part in the path of movement of the dog or finger as it is moved to operative position to cause the holding means to rotate the hopper in a backward position when a filling carrier is improperly positioned in the path of the transferrer when a change of filling is called.

5. In a filling replenishing loom, the combination of a rotary hopper, a transferrer, a dog connected to the transferrer, a pivotally mounted holding pawl carrier, a swinging

detent having a part adapted to be engaged by the dog as the latter is moved toward operative position on call for replenishment of filling, and connections between the swinging detent and holding pawl carrier for operating the holding pawl carrier to effect rotary movement of the hopper by the holding pawl carrier when a filling carrier is not in proper position for transfer and filling is to be changed.

6. In a filling replenishing loom, the combination of a rotary hopper for holding a supply of filling carriers, a transferrer, means for operating the transferrer to transfer a filling carrier from the hopper to the shuttle, means for holding the hopper from rotary movement with a filling carrier in position for transfer, a pivotally mounted detent adapted to be rocked by the dog or finger as it moves to operative position, and connections between the pivotally mounted detent and hopper holding means to actuate the latter and cause it to rotate the hopper when a filling carrier is not in proper transferring position on call for replenishment of filling.

7. In a filling replenishing loom, the combination of a rotary hopper, means for holding the hopper from rotation with a filling carrier in position for transfer, a transferrer, and means acting through the holding means alternatively to rotate the hopper backward or prevent operation of the transferrer when a filling carrier is improperly positioned for transfer in the path of the transferrer upon call for replenishment of filling.

8. In a filling replenishing loom, the combination of a rotary hopper for holding a supply of filling carriers, a transferrer for transferring filling carriers from the rotary hopper to the shuttle, means for rotating the hopper, means for holding the rotary hopper from rotation when a filling carrier is in position for transfer, and a detent connected to the holding means for rotating the hopper through the holding means when a filling carrier is improperly positioned for transfer in the path of the transferrer.

9. In a filling replenishing loom, the combination of a rotary hopper for holding a supply of filling carriers, a transferrer for transferring filling carriers from the rotary hopper to the shuttle, means for rotating the hopper, means for holding the rotary hopper from rotation when a filling carrier is in position for transfer, and means for giving the rotary hopper a backward movement when a filling carrier is improperly positioned for transfer in the path of the transferrer upon call for replenishment of filling to carry the improperly positioned filling carrier out of the path of the transferrer.

10. In a filling replenishing loom, the combination of a rotary hopper, a trans-
ferrer, a dog connected to the transerrer,
a holding pawl carrier, a detent pivotally
5 mounted between the dog and holding pawl
carrier and adapted to be engaged by the
dog as the latter is moved on call for re-
plenishment of filling, and connections be-
tween the pivotally mounted detent and
holding pawl for operating the latter by the 10
former.

In testimony whereof I have signed my
name to this specification.

EDWARD S. STIMPSON.
